UNITED STATES PATENT OFFICE.

OSWALD S. PULLIAM, OF PITTSBURG, PENNSYLVANIA.

CAR-BODY UNDERFRAME CONSTRUCTION.

No. 813,667.

Specification of Letters Patent.

Patented Feb. 27, 1906.

Application filed September 23, 1905. Serial No. 279,804.

To all whom it may concern:

Be it known that I, OSWALD S. PULLIAM, a citizen of the United States, residing at Pittsburgh, in the county of Allegheny and State 5 of Pennsylvania, have invented new and useful Improvements in Car-Body Underframe Construction, of which the following is a specification.

The object of my invention is to provide a 10 new and improved car-body underframe construction; and to this end the present invention consists of a car-body underframe, in the novel features of construction, and in the combination of parts, all as fully hereinafter described and claimed.

In the accompanying drawings, which illustrate applications of my invention, Figure 1 is a broken plan view of a car-body underframe constructed in accordance with my invention; Fig. 2, a part-sectional view and a part-elevational view, the section being taken on line II II of Fig. 1; Fig. 3, a broken sectional view taken on line III III of Fig. 1; Fig. 4, a detail central perspective view of body-bolster; Fig. 5, a detail perspective view of draft-rigging carrier; Fig. 6, a plan view of modified form; Fig. 7, a part-sectional view and a part-elevational view, the section being taken on line VII VII of Fig. 6; Fig. 8, a detail sectional view taken on line VIII VIII of Fig. 6; Fig. 9, an inverted perspective view of the body-bolster of the form of Fig. 6, and Fig. 10 an inverted perspective view of a part of the draft-rigging carrier.

Referring to the drawings, I have shown two center sills 2 in the form of channels; but I do not desire to be limited to the employment of two center sills of the form illustrated, as my invention contemplates the use 40 of one center sill of any suitable form or of two or more center sills of other shapes than channels.

The body-bolster 3 and the draft-rigging carrier 4 both differ somewhat in the two 45 forms of my invention as illustrated by the drawings. In both forms, however, the ends of the center sills, the draft-rigging carrier, and the body-bolster are securely locked together and constitute a very desirable construction for a metallic car-body underframe.

In the form of Fig. 1 the body-bolster 3, comprising the top member 5, the bottom member 6, and the vertical web 7, is formed with a centrally-disposed recess 8 and with 55 ledges 9 and 10. Recess 8 is adapted to receive the draft-rigging carrier and the ends of

the two center sills. The draft-rigging carrier constitutes a continuation of the center sills and is constructed with an engaging plate 11, adapted to fit into the recess 8 and 60 be supported on the ledges 9 and 10. The bolster is provided with a center bearing-plate 12, and projecting inwardly from the side walls of ledges 9 I employ a series of lugs or projections 13. These lugs 13 may be 65 either cast of the metal of which the bolster is formed or by placing fins or rivets in the mold preparatory to casting the bolster proper and then casting the bolster around said projections. In Fig. 3 of the drawings I 70 have particularly shown this latter construction. The center sills 2 are formed with a series of holes adapted to receive the lugs or projections 13 of the bolster when the ends of the sills are placed with the bolster preparatory 75 to securing said sills to the bolster by means of the said lugs. After securing the sills to the bolster the draft-rigging carrier, which constitutes a filler, is placed in position within the recess of the body-bolster and rigidly secured thereto by bolts or rods, (not shown,) 80 which are passed through holes 14 of the engaging plate 11 and through apertured ears 15 of the bolster. If desirable, lugs 16 may be formed on the draft-rigging carrier, as 85 shown by Fig. 5, against which the ends of the sills abut when placed in position.

In the form of Fig. 6 instead of placing the draft-rigging carrier down into the body-bolster, as in the form of Fig. 1, it is inserted upwardly into the recess 8. In this modified form the center bearing-plate 12 is formed on the draft-rigging carrier.

If desirable, the engaging lugs formed on the body-bolster may be of such a length as to 95 extend through the metal sill or sills and engage the metal filler.

What I claim is—

1. A car - body underframe construction comprising a metal center sill, a metal body-bolster formed with a recess to receive the center sill, and a metal draft-rigging carrier interlocked, substantially as set forth. 100

2. A car - body underframe construction comprising a metal center sill, a metal body-bolster formed with a recess and with lugs arranged to engage the center sill, and a metal draft - rigging carrier, substantially as set forth. 105

3. A car - body underframe construction 110 comprising a metal body-bolster formed with a recess, a metal center sill extending into the

- recess, and a metal draft-rigging carrier located in the recess, substantially as set forth.
4. A car - body underframe construction comprising a metal body-bolster having a central recess and provided with lugs projecting into the recess, a metal sill in the recess, a filler in the recess, said lugs extending through the sill and adapted to engage the filler, substantially as set forth.
- 10 5. A car - body underframe construction comprising a metal body-bolster formed with a recess and provided with lugs projecting into the recess, center sills in the form of channels extending into the recess, a filler in the recess located between the sills, said lugs engaging the sills, substantially as set forth.
- 15 6. A car - body underframe construction comprising a metal body-bolster formed with
- a recess, center sills in the form of channels extending into the recess, and a metal draft-rigging carrier located in the recess between the center sills, substantially as set forth. 20
7. A car - body underframe construction comprising a metal body-bolster formed with a recess, center sills extending into the recess, 25 a metal draft-rigging carrier extending into the recess between the center sills, said bolster, sills and carrier interlocked, substantially as set forth.

In testimony whereof I affix my signature 30
in presence of two subscribing witnesses.

OSWALD S. PULLIAM.
